UNITED STATES PATENT OFFICE.

JAMES BROWN, OF BAY RIDGE, NEW YORK.

IMPROVEMENT IN FIBER-CLEANING MACHINES.

Specification forming part of Letters Patent No. 116,546, dated July 4, 1871.

To all whom it may concern:

Be it known that I, JAMES BROWN, of Bay Ridge, in the county of Kings and State of New York, have invented a new and useful Improvement in Fiber-Cleaning Machine; and I do hereby declare that the following is a full and exact description of the same, reference being had to the accompanying drawing and to the letters of reference marked thereon.

This invention has for its object the production of a machine which shall be capable of thoroughly cleaning and dressing vegetable fibers in an expeditious and economical manner, and consists in certain details of construction, as will be fully described hereinafter.

In the drawing, Figure 1 represents a side elevation of my improved machine; Fig. 2, a plan view; and Fig. 3, views of the heckles or teeth detached.

To enable others skilled in the art to make and use my invention, I will now proceed to describe fully its construction and operation.

A represents a frame-work, of any suitable construction. B represents a cylinder, having a shaft, b, hung in proper bearings in the frame A, and provided with a suitable handle, b'; or other means for giving it a revolving motion. The shaft b is so constructed and hung in the bearings as to be capable of a longitudinal movement from side to side of the frame. This result is preferably accomplished by lengthening the bearings of the shaft, as shown in Fig. 2, and providing it with suitable shoulders for properly limiting its movement. G represents a flap or door located in the cylinder B, which is intended for gripping one end of the fibrous substance to be treated. D represents a series of heckles or teeth, formed of single teeth, d, as shown, which are constructed preferably of steel, with tapering points, as clearly indicated in the drawing. The members of the series are contiguously arranged in a continuous

row at one end of the frame B, as is clearly shown in the drawing. E represents a trough for containing water, in which the lower portion of the cylinder revolves.

The operation is as follows: One end of the fibrous substance to be treated is securely attached to the cylinder by means of the gripping device C. The cylinder is then rapidly revolved in any proper manner, by which means the free ends of the fibrous substance are thrown outward by centrifugal force, and are caused to come into contact violently with the heckles or teeth D, through which they are drawn by the continued revolution of the cylinder. As the points of the teeth are made tapering, and as their larger portions lie contiguous to each other, it follows that a wedge-shaped opening is left between the teeth into which the fibrous substance is whipped. It therefore follows, necessarily, that the teeth not only serve to divide the fiber, but also to scrape it as it is drawn through the lower part of the wedge-shaped opening. By giving the cylinder the slight lateral play permitted by the longitudinal movement of the shaft every portion of the substance being treated is continuously exposed to the action of the teeth.

Having thus fully described my invention, what I claim as new, and desire to secure by Letters Patent, is—

1. The heckle D, composed of the series of hook-shaped teeth d, arranged in a continuous line, with their bases contiguous, and having tapering points, in combination with the cylinder B and the frame A, as described.

2. The cylinder B, adapted to move laterally, as described, in combination with the stationary heckles upon the frame A, as set forth.

JAMES BROWN.
